UNITED STATES PATENT OFFICE

JOSEPH FRANCIS DONNELLY, OF LEMONT, ILLINOIS

WINDOW

Application filed November 5, 1928. Serial No. 317,448.

This invention relates to windows and the like, but more particularly relates to windows which may be revolved or turned so that the outside thereof will be brought to a position facing the inside of the building. An object of the invention is to provide a means whereby a window may be entirely cleaned from the inside, thereby eliminating the danger and expense which is always attendant upon cleaning windows from the outside.

A further object is to provide a means for easily repairing the window weight cords, the window sash or frame, or for putting the glass from the inside.

The window sash or frame may be made from any suitable material such as wood or metal. The wall frame may be made slightly cone shaped, being wider at one end than the other. The sash frame may also be cone shaped, but of such dimensions as to fit into the wall frame. Preferably the sash frame forms a box with the wall frame to permit free movement of the sash weights which are supported on the sash frame.

Other advantages and objects of my invention will appear hereinafter in the detailed description which follows.

Fig. 1 is a front elevation showing the window in its normal stationary position, taken on line 1—1 Fig. 2 with the sash frame raised.

Fig. 2 is a side elevation, partly in section, taken on line 2—2 on Fig. 1.

Fig. 3 is a cross section, taken on line 3—3 Fig. 1.

Fig. 4 is a front elevation showing the sash frame lowered so as to permit the turning of the window.

In the drawings W is a wall frame comprising two parallel vertical strips 1 and 2 joined at the top by parallel cross strip 3 and at the bottom by parallel cross strip 4. The vertical strips 1 and 2 are tapered as shown, having their largest ends at the top. The sash frame is composed of vertical strips 5 and 6 which form a box-like structure for the reception of the window weights and cords shown at 7. The outer surfaces of the strips 5 are formed with a convex curve and

the inner surfaces of the vertical strips of the wall frame are formed with a concave curve, as shown in Fig. 3. The strips of the sash frame 5 are provided with V-shaped packings 8.

The vertical members 5 of the sash frame are tapered as shown in Fig. 1, having their larger ends at the bottom. A metallic socket is installed in the center of the upper cross strip 3, which is adapted to receive a vertical pin 10, which is centrally mounted on the upper cross piece 11 of the sash frame 12. A threaded socket 13, is mounted centrally in the lower cross piece 4 of the wall frame. A spindle 14 has its lower end threaded into the socket 13 and its upper end swiveled in a bearing 15 in the lower cross piece 16 of the sash frame. The spindle 14 may be turned, thus raising or lowering the sash frame and windows 18 and 19 as desired.

The wall frame is provided with doors 20 and 21 which close off the open space beneath the sash frame when the sash frame is in its elevated position, as shown in Figs. 1 and 2. The doors 20 and 21 are provided with suitable hinges and latches.

When it is desired to revolve the sash frame and windows so as to give access from the inside of the building to the outside of the windows, the spindle 14 is revolved by means of a hand wheel 17 so as to lower the sash frame into the position shown in Fig. 4. Due to the tapered contour of the vertical pieces of the sash frame and wall frame, the sash frame will be clear of the wall frame when it is in lowered position. The sash frame may then be revolved, with the windows carried thereby, at will and free access may be had from the inside of the building to both sides of the windows. When it is desired to return the windows and sash frame to the upper position wherein the sash frame makes close contact with the wall frame, the hand wheel 17 is revolved so as to raise the sash frame into the position shown in Fig. 1.

In this position the packings 8 will form a tight joint between the sash frame and the wall frame. In this raised position the windows may be raised and lowered within the sash frame in the ordinary manner. At this

time the doors 20 and 21 may also be closed and latched. As will be seen from an inspection of Fig. 2, the door 20 overlaps the lower cross piece 16 of the sash frame and the door 21 abuts a strip 22 on the same cross piece, thus effectively holding the sash piece in place, and at the same time screening the open space which contains the hand wheel 17 and spindle 14.

10 It will thus be seen that I have provided a window which fulfills all the objects of my invention as heretofore set forth.

Having described my invention, what I claim is:

15 1. In a device of the character described, a wall frame and a sash frame so constructed relative to each other that the sash frame may be revolved independently of and moved longitudinally relative to the wall frame.

20 2. In a device of the character described, a wall frame and a sash frame so constructed relative to each other that the sash frame may be revolved on an axis passing through the wall frame and moved longitudinally relative to said frame.

25 3. In a device of the character described, a wall frame, a sash frame so constructed as to have relative longitudinal movement with respect to each other and pivoted members connecting the wall frame with the sash frame so constructed as to permit the rotation of the sash frame relative to the wall frame.

35 4. In a device of the character described, a wall frame, a sash frame, a pivoted member between one side of the sash frame and the wall frame adapted to permit longitudinal and rotary motion of the sash frame relative to the wall frame and a pivoted member between the opposite side of the sash frame and the opposite side of the wall frame so constructed as to permit longitudinal and rotary motion of the sash frame relative to the wall frame.

45 5. In a device of the character described, a wall frame, a sash frame, a pivoted member between one side of the sash frame and the wall frame so constructed as to permit longitudinal and rotary motion of the sash frame relative to the wall frame, a pivoted member between the opposite side of the sash frame and the opposite side of the wall frame so constructed as to permit longitudinal and rotary motion of the sash frame relative to the wall frame and means operating in conjunction with said last named pivoted member for causing longitudinal movement of said sash frame relative to said wall frame.

55 6. In a device of the character described, a wall frame and a sash frame so constructed as to have pivotal and longitudinal motion relative to each other, said wall frame and sash frame having walls of such contour that longitudinal movement of said sash frame relative to said wall frame will place said

sash frame in a position of free rotary movement relative to said wall frame.

7. In a device of the character described, a wall frame and a sash frame so constructed as to have pivotal and longitudinal motion relative to each other, said sash frame and wall frame having oppositely tapering sides whereby longitudinal movement of said sash frame relative to said wall frame places said sash frame in a position of free rotary movement relative to said wall frame.

8. In a device of the character described, a wall frame and a sash frame so constructed as to have pivotal and longitudinal motion relative to each other, said sash frame and wall frame having oppositely tapering sides whereby longitudinal movement of said sash frame relative to said wall frame places said sash frame in a position of free rotary movement relative to said wall frame and means to cause longitudinal movement of said sash frame relative to said wall frame.

9. In a device of the character described, a wall frame and a sash frame having pivoted connections with each other so constructed as to permit pivotal and longitudinal motion of said sash frame relative to said wall frame, said sash frame and wall frame having oppositely tapering sides whereby longitudinal movement of said sash frame relative to said wall frame places said sash frame in a position of free rotary movement relative to said wall frame and means operating in conjunction with one of said pivots adapted to cause longitudinal motion of said sash frame relative to said wall frame.

10. In a device of the character described, a wall frame having tapered vertical inner walls, a sash frame having oppositely tapered outer walls, said wall frame being of greater vertical length than said sash frame, a pivot pin and socket connection between the upper ends of said sash and wall frames so constructed as to permit rotary and longitudinal movement of said sash frame relative to said wall frame and a threaded pin and socket connection between the lower ends of said sash and wall frames so constructed as to permit rotary motion of said sash frame relative to said wall frame and cause longitudinal movement of said sash frame relative to said wall frame whereby said sash frame is placed in a position of free rotary movement with respect to said wall frame when said sash frame is moved in one direction and placed in tight contact with said wall frame when said sash frame is moved in the opposite direction.

JOSEPH FRANCIS DONNELLY.
